UNITED STATES PATENT OFFICE.

JOHN T. FITZPATRICK, OF COVE, ARKANSAS.

LOOM.

Application filed January 14, 1921. Serial No. 437,279.

To all whom it may concern:

Be it known that I, JOHN T. FITZPATRICK, a citizen of the United States, residing at Cove, in the county of Polk, and State of Arkansas, have invented new and useful Improvements in Looms, of which the following is a specification.

This invention relates to looms, and the principal object of the invention is to provide means for reciprocating the bobbin-carrying members.

The invention also relates to the means for transferring the bobbin from one carrying member to the other.

The invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like 25 or corresponding parts throughout the several views, and in which:—

Figure 1 is a longitudinal sectional view, showing a part of a loom constructed in accordance with my invention.

Figure 2 is a longitudinal sectional view with the parts in a position to release the bobbin.

Figure 3 is a diagrammatic view showing how the carrying member and bobbin pass 35 through the warps.

Figure 4 is a section on line 4—4 of Figure 2.

In these views, the frame of the loom is indicated at 1, and slidingly mounted on 40 the lay 1' of said frame is a pair of carrying members 2, one of which is located at each side of the loom. Each member comprises a body 3 and a stem 4, said stem receiving the bobbin 5. The stem 4 is slidably mounted in a recess 3' in the body and is normally held in its outer position by the spring 3'' which is located in said recess. A pin 3*, passing through the stem and engaging the slots in the body, acts to 50 limit the movement of the stem. Each of the members is reciprocated by means of the endless belt 6 which passes over the rollers 7, one of which is driven in any suitable manner. The endless belt carries a projection 8, which is adapted to strike the body

3, so as to force the same forwardly when the projection is on the upper stretch of the belt. As the projection reaches the outer roller and starts to move downwardly, it will disengage the body and a spring 9 connecting the body with the frame will snap said body back to its original position. As the projection comes around again, it will strike the body and move the same outwardly, so that the said body is moved outwardly at intervals.

Each of the stems 4 is provided with a groove 10, which receives a latch member 11. This member is pivoted intermediate its ends to the stem by the pin 12. The front end 70 of said member is provided with a latch head 13 and its other end projects upwardly to form a trigger 14. A roller 14' is carried by said trigger to engage the pointed end of the frame. The front end of the groove 75 is deep enough to admit the latch head 13 to permit the bobbin to pass over the same. A spring latch 15 is secured to each side of the frame in a position to engage the bobbin when the carrying member is in its innermost position.

The bobbin is placed on the spindle 4 of the first turning member and the end of the thread secured to the side of the frame. The second member is then moved by the 85 endless belt until its spindle strikes the spindle of the first member and pushes the same inwardly. This action will cause the roller on the trigger of the first member to engage the pointed end of the frame, thus depressing the latch head 13 to permit further movement of the parts to shove the spindle of the first member through the bobbin and permit the spindle of the second member to enter the bobbin. This movement will continue until the spindle of the second member has passed entirely through the bobbin, shoving the spindle of the first member ahead of it until the latch head 13 of the second spindle will engage the end of the 90 bobbin and thus secure the bobbin on said second spindle. At this time the projection on the endless belt will release the second member so that the spring 9 of said second member will snap the same backwardly into its normal position, carrying the bobbin with it. This will stretch the thread and then after the warps have been moved the first member will advance, seize the bobbin from the second member and 100 105 110

carry it back to the starting point. The thread is thus stretched again and after movement of the warps the second member is advanced to seize the bobbin and this action is kept up to carry the thread back and forth through the warps. Then latches 15 hold the bobbin against movement while the carrying members are at rest.

As my invention relates wholly to the 10 means for passing the bobbin through the warps, as shown in Figure 3, it is not thought necessary to illustrate or describe other portions of the loom, as such parts are of the ordinary or any desired construction.

15 The invention can be applied to manually operated looms or to power driven looms.

The warps and the operating means, as well as the sley, have not been shown, as these parts are similar to those now used 20 in the art.

What I claim is:—

1. A loom of the class described, comprising a pair of bobbin carriers, springs for holding the same in retracted position, an 25 endless belt for each carrier, a projection on each belt for engaging the carrier to

project the same forwardly and means for rotating the belts.

2. A loom of the class described, comprising a pair of bobbin carriers, each consisting of a body part and a stem, latch means on said stem, a trigger for depressing said latch means, springs for holding the carriers in retracted position, an endless belt for each carrier, a projection on each belt 30 for engaging the carrier to project the same forwardly and means for rotating the belts. 35

3. A loom of the class described comprising a pair of bobbin carriers, each consisting of a body part and a stem movably mounted in the body part, spring means for holding the stem in its outer position, latch means on said stem, a trigger for depressing said latch means, springs for holding the carriers in retracted position, an endless belt 40 for each carrier, a projection on each belt for engaging the carrier to project the same forwardly and means for rotating the belts. 45

In testimony whereof I affix my signature. 50

JOHN T. FITZPATRICK.
